R. P. Holmes.

United States Patent Office.

B. P. HOLMES, OF PHILADELPHIA, PENNSYLVANIA.

Design No. 2,753, dated August 20, 1867.

DESIGN FOR AN INK-BOTTLE.

The Schedule referred to in these Letters Patent and making part of the same.

TO ALL WHOM IT MAY CONCERN:

Be it known that I, B. P. HOLMES, of Philadelphia, county of Philadelphia, State of Pennsylvania, have invented or produced a new and original Design for an Ink-Bottle and Stand; and I do hereby declare that the accompanying drawings, and the following explanation thereof, form a full, clear, and exact description of the said design.

Figure 1 is a front view, and

Figure 2 a plan view, representing an inkstand made in accordance with my new design.

The inkstand is square at the base *a*, and is slightly inclined on all four sides. In the top *b* are two depressions, *d*, forming longitudinal curves for the reception of pen-holders, and between these depressions is the cylindrical neck *e* of the inkstand, having a rim, *f*, at its upper edge.

I claim the design for an ink-bottle and stand, substantially as shown in and by the accompanying drawing.

In testimony whereof I have signed my name to this specification in the presence of two subscribing witnesses.

B. P. HOLMES.
